Inventor:

UNITED STATES PATENT OFFICE.

CLARENCE LEO BEST, OF OAKLAND, CALIFORNIA, ASSIGNOR TO THE HOLT MANUFACTURING COMPANY, OF STOCKTON, CALIFORNIA, A CORPORATION OF CALIFORNIA.

TRACK-LAYING TRACTOR.

1,395,029.

Specification of Letters Patent. Patented Oct. 25, 1921.

Application filed October 8, 1917. Serial No. 195,440.

To all whom it may concern:

Be it known that I, CLARENCE LEO BEST, a citizen of the United States, residing at Oakland, in the county of Alameda and State of California, have invented certain new and useful Improvements in Track-Laying Tractors, of which the following is a specification, reference being had therein to the accompanying drawing.

10 This invention relates to track laying tractors and more particularly to track laying tractors of the type in which the endless tracks are capable of yielding oscillatory movement to automatically accommodate 15 themselves to broken and uneven ground surface.

The object of the invention is to provide an improved tractor of the type referred to made up of a minimum number of parts, 20 to provide improved spring mechanism for resisting upward tilting movement of the endless tracks, to provide improved supporting means for the motor and allied devices, to provide for the embodiment of the motor 25 and allied devices in the form of a strong compact unitary structure, and for an improved connection of the same with the endless tracks and the connection of the endless tracks together whereby a construction 30 is produced that is practically frameless and of an extremely simple and compact nature which will be strong and efficient in use and can be manufactured very cheaply.

The invention, with other objects and advantages thereof and the particular construction, combination and arrangement of parts comprising the same will be understood from the hereinafter contained detail description when considered in connection 40 with the accompanying drawings forming a part hereof and illustrating a preferred embodiment of the invention.

In the drawings:

Figure 1 is a side elevation of a tractor 45 constructed in accordance with the present invention.

Fig. 2 is a top plan view.

Fig. 3 is an end elevation with parts shown in section.

Fig. 4 is a section on the line 4—4 of Fig. 2, the power shaft and gearing being omitted.

Fig. 5 is a detail top plan view of the supporting member, and

Fig. 6 is a detail side elevation and partial 55 section of the supporting member.

While I have illustrated a special embodiment of the invention in the drawings, I desire it to be understood that changes and obvious modifications of the structure shown, and the embodiment of the invention in other forms, as will appeal to those skilled in the art and within the scope of the appended claims may be practised without departing from the spirit of the invention.

In accordance with the invention, the motor and allied device are all mounted on a single member or part, said part being shaped to form a carrier and housing for the operating mechanism and constituting the main frame of the machine. This preferably takes the form illustrated in the drawings, a hollow casting tapering from front to rear and comprising a central longitudinally extending bottom portion 1 and side portions 2 substantially U-shaped in cross section extending below the lower face of the central bottom portion 1, the side portions 2 being of greatest height at a point 3 intermediate the ends thereof and from thence extending in a gradual curve or incline from said points 75 to the opposite ends of the casting, said U-shaped side portions 2 constituting in effect reinforcing ribs extending the full length of the casting at each side thereof, the structure thus produced affording a very 80 strong support and forming a partial housing for the parts. The upper face of the central bottom portion 1 of the casting is preferably shaped as shown with the spaced 85 raised portions 4 to accommodate the motor 90 and allied devices or parts. 5 designates the motor at the front of the casing shown as an internal combustion engine, 6 the clutch, 7 the change speed transmission, and 8 a pinion loosely mounted on the transverse 95 two part drive shaft 9 supported in bearings 10 at the rear end of the supporting member or casting. 11—11' are clutch members 100 adapted to couple the two sections of shaft 9 to the pinion 8, and 12—12' are drive 105 pinions located at the outer ends of the said shaft sections. The motor and allied parts or devices may be of any approved type, and I am therefore only indicating in the drawings and describing in a general way one 105 of the well known constructions. The engine and base are preferably formed integral as shown and secured to the supporting member or casting in any suitable way. A casting or cover 13 is detachably connected with 110

the supporting member or casting forming therewith a complete housing for the motor devices located in rear of the motor.

The supporting member or casting is supported at its rear end upon an axle 14 to which is pivotally connected the endless tracks, the supporting member being provided with a bearing 15 engaging the axle 14 intermediate its ends, and the tracks being connected with the axle near the ends thereof to extend along opposite sides of the supporting member or casting. The endless tracks may be of any suitable form. In the construction illustrated in the drawings, each endless track comprises a pair of spaced bars 16 rigidly secured together. At the rear end the bars 16 are provided with a bearing 17 for the axle 14 and rotatably mounted on the axle between the bars is a driving sprocket 18. 19 are securing nuts on the ends of the axle 14. At the forward end of the bars 16 an idler wheel 20 is mounted on a short shaft 21 supported in bearings 22, and trained over the driving sprocket 18 and idler wheel 20 is the endless traction chain 23. The driving sprockets 18 are provided with internal gears 19^a with which the driving pinions 12-12' mesh. 25 designates guide rollers for the chain rotatably supported on the bars 16.

Between the frame or casting and the endless tracks is provided a yielding member which is disposed transversely of the endless tracks and the supporting frame. In the special embodiment of the invention illustrated in the drawings the yielding member takes the form of a leaf spring 26, said spring having its opposite ends engaging housings 27 on the bar 16 of the endless tracks, and the forward end of the supporting frame or casting rests upon the spring intermediate its ends, the supporting frame being formed with a bearing portion to engage the yielding member 26. The bearing portion may be slightly curved as shown to correspond with the normal curvature of the yielding member 26, and the yielding member is preferably secured to the supporting member by clips or U-bolts 29.

As will be understood each of the endless tracks are capable of independent yielding oscillatory movement in a vertical plane to

independently accommodate itself to varying ground contours. Through the medium of the clutch members 11-11' the endless tracks can be separately driven, the guiding of the tractor being effected in this way.

It will be observed that the construction hereinbefore described is composed of only three main parts, the supporting member or casting and the pair of endless tracks. The axle forms the means for connecting the supporting member to the endless tracks and also the endless tracks together. The special spring mechanism provided is simple and effective. The motor and allied devices are in the form of a strong compact unitary structure, the resulting construction being practically frameless, of an exceedingly simple, compact nature, that will be strong and efficient in use and can be manufactured very cheaply.

What I claim is:

1. In a vehicle, a main frame comprising a hollow casting tapering from front to rear and having a central longitudinally extending bottom portion and side portions, the latter being substantially U-shaped in cross section and constituting in effect reinforcing ribs extending the full length of the frame at each side thereof.

2. In a vehicle, a main frame comprising a hollow casting tapering from front to rear and having a central longitudinally extending bottom portion and side portions extending below said bottom portion and substantially U-shaped in cross section, said side portions being inclined downwardly from the front end of the main frame to a point intermediate the ends, and thereafter inclining upwardly to the rear end of said main frame.

3. In a vehicle, a main frame comprising a hollow casting having a bottom part and side portions, said side portions being substantially U-shaped in cross section and extending below the bottom part and constituting reinforcing ribs.

In testimony whereof I hereunto affix my signature in the presence of two witnesses.

CLARENCE LEO BEST.
